UNITED STATES PATENT OFFICE.

WILLIAM SHIRLEY, OF COVENTRY, ENGLAND.

DRESS-GUARD ATTACHMENT.

SPECIFICATION forming part of Letters Patent No. 606,492, dated June 28, 1898.

Application filed September 15, 1897. Serial No. 651,769. (No model.) Patented in England September 17, 1896, No. 20,597; in France November 10, 1896, No. 261,146, and in Germany November 10, 1896, No. 92,855.

To all whom it may concern:

Be it known that I, WILLIAM SHIRLEY, a subject of the Queen of Great Britain, residing at Coventry, England, have invented a new and Improved Bicycle Quadrant Attachment for Dress-Guards, of which the following is a full, clear, and exact description.

My invention relates to a device adapted for attaching dress-guards of bicycles to the frame or the axle of the machine, for which Letters Patent were granted to me in England, No. 20,597, dated September 17, 1896; in France, No. 261,146, dated November 10, 1896, and in Germany, No. 92,855, dated November 10, 1896.

The object of the invention is to provide an attachment whereby a dress-guard may be quickly and conveniently applied to bicycles adapted for women's use and whereby the guard may be kept stretched perfectly tight and may be readily removed whenever necessary or desirable.

Another object of the invention is to provide a fastening device of the character above described which will be not only durable and economic, but also exceedingly light.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the rear portion of a bicycle, illustrating the application of the attaching device for the dress-guard. Fig. 2 is an enlarged side elevation of the attaching device, a part thereof being in section. Fig. 3 is a vertical section on the line 3-3 of Fig. 2. Fig. 4 is a side elevation of a slightly-modified form of the attaching device, and Fig. 5 is a section through the keeper of the modified form of the attaching device and the member of the bicycle-frame to which it is applied.

A represents a rear upper brace of a drop-frame bicycle; B, the axle of the rear wheel; C, the rear wheel; D, the rear lower brace of the frame, and E the mud-guard.

The attaching device consists of a keeper F

and a quadrant-latch F'. The keeper F consists of a body having an opening 11 therein and provided at the top with an offset or curved flange 12, the flange being supported at a point beyond the outer face of the body, occupying a vertical position. The flange 12 of the keeper is provided upon its outer face, at or near its center, with a stud 13. The quadrant-latch consists of a segmental body-plate 14, provided with a keyhole-slot 15, adapted to receive the stud of the keeper F. Two or more (ordinarily three) cylinders 16 are formed at the upper edge of the segmental body-plate 14 of the latch, and in each of the said cylinders a piston 17 is held to slide, and within each cylinder a spring 18 is contained bearing against the head of the piston and against the outer end of the cylinder. The rod of each piston extends out through the upper end of the cylinder in which it is located and terminates in an eye 17a.

In the ordinary form of the device a serpentine rod 19 is passed through the eyes 17a of the pistons, and the lower threads of the guard F² are passed around the upwardly-extending loop portions of the bar 19. Instead of the rod 19 being provided with the loops, as shown in Fig. 2, eyes may be substituted for said loops. The guard may be woven, knotted, or knitted, as desired, and preferably at each upper point of the dress-guard a clip 21 is secured, which clips are made to enter the usual openings in the mud-guard E. After the dress-guard has been secured to the mud-guard it is drawn downward, placing the springs 18 in the cylinders under tension until the stud of the keeper has entered the slot 15 in the body of the quadrant-latch. The keeper F of the device may be and usually is placed upon the outer end of the rear axle B and secured in place by the same nut which is utilized to hold the frame in proper position relative to the hub of the rear wheel.

In Figs. 4 and 5 I have illustrated a slight modification in the device, in which the latch F³ is provided with but two cylinders 16, and at the end of each piston-rod 17 a ring 22 is located, in which the loops at the lower end of the dress-guard are gathered. The difference in construction between the form shown

in Fig. 4 and that shown in Fig. 2 consists principally in the formation of the keeper F⁴, the said keeper consisting of a body 23, shaped substantially as a clip, the said body being 5 adapted to be clamped around the upper rear brace A of the frame, said body 23 being provided with a stud 24, as in the other form of keeper.

Having thus described my invention, I 10 claim as new and desire to secure by Letters Patent—

1. An attaching device for bicycle dress-guards, consisting of a keeper, and a latch adapted for locking engagement with the 15 keeper and having casings formed upon its body the said latch being provided with spring-controlled members having movement in the said casings and arranged for attachment to the dress-guard, for the purpose set 20 forth.

2. In a bicycle dress-guard, a latch adapted for attachment to a bicycle-frame and comprising a segmental body-plate having casings formed at its upper edge, and a spring-pressed 25 rod arranged in each casing and extending out through the upper end thereof, the said rods being arranged for attachment to a dress-guard substantially as set forth.

3. In an attaching device for bicycle dress- 30 guards, a latch arranged for attachment to a bicycle-frame, a cylindrical casing carried by the latch-body, and a spring-controlled rod having guided movement in the casing and terminating at its upper end in an eye, the 35 said rod being arranged for attachment to a dress-guard, for the purpose specified.

4. In a dress-guard for bicycles, an attaching device for the said guard, consisting of a keeper adapted to be attached to the bicycle- 40 frame, a latch arranged for locking engagement with the keeper, and spring-controlled pistons arranged for engagement with the

lower portion of the dress-guard, for the purpose set forth.

5. In an attaching device for bicycle dress- 45 guards, the combination, with a keeper adapted for attachment to the frame, the said keeper being provided with a stud, of a latch provided with a slot to receive the stud of the keeper, casings formed upon the body of the 50 latch, and spring-controlled pistons located within the said casings and extending outwardly therefrom.

6. In an attaching device for bicycle dress-guards, the combination with a keeper adapted for attachment to the frame, the said keeper being provided with a stud, of a latch provided with a slot to receive the stud of the keeper, casings formed upon the body of the 55 latch, spring-controlled pistons located within 60 the said casings and extending outwardly therefrom, and a bar connecting the pistons in the said casings, the said bar being adapted to receive the loops at the lower end of the dress-guard, as and for the purpose specified. 65

7. The combination with a mud-guard, and a dress-guard adapted for attachment at its upper portion to the said mud-guard, of a keeper adapted to be attached to the bicycle-frame and having on its outer face a projecting 70 stud and a latch comprising a body-plate having a slot to receive the stud of the keeper the said body-plate being provided with extensions from its upper edge forming guideways and spring-controlled rods having movement in the said guideways, the upper ends of the said rods being arranged for engagement with the lower portion of the dress-guard, for the purpose set forth. 75

WILLIAM SHIRLEY.
